UNITED STATES PATENT OFFICE.

RICHARD W. HANNA, OF RICHMOND, CALIFORNIA, ASSIGNOR TO STANDARD OIL COMPANY OF CALIFORNIA, OF SAN FRANCISCO, CALIFORNIA, A CORPORATION OF CALIFORNIA.

PROCESS FOR THE CONTINUOUS PRODUCTION OF LOW-BOILING-POINT HYDROCARBONS FROM PETROLEUM OILS.

1,419,378.

Specification of Letters Patent. Patented June 13, 1922.

Application filed January 19, 1920. Serial No. 352,416.

To all whom it may concern:

Be it known that I, RICHARD W. HANNA, a citizen of the United States, residing at Richmond, in the county of Contra Costa and State of California, have invented a new and useful Process for the Continuous Production of Low-Boiling-Point Hydrocarbons from Petroleum Oils, of which the following is a specification.

10 This invention relates to the art of producing low boiling point hydrocarbons, such for example as motor spirits, from higher boiling point petroleum oils, crude oils and residuums.

15 I have discovered that the distillate produced by the generally accepted processes of destructive or ordinary distillation forms carbon and carbonaceous matter when further destructive distillation thereof is attempted. This is due to the reduced hydrogen content of the distillate produced by such destructive or ordinary distillation. This can be overcome by preserving the hydrogen content by distillation under a reduced pressure less than atmospheric preventing decomposition or the formation of unsaturated hydrocarbons.

20 The distillation of a petroleum oil under a reduced pressure sufficient to lower the vaporizing temperature below said petroleum oil decomposing or cracking temperature conserves the hydrogen content of the oil so that the formation of unsaturated hydrocarbons or aromatic hydrocarbons is substantially prevented. When submitted to a cracking temperature and pressure certain classes of unsaturated and aromatic hydrocarbons tend to polymerize, resulting in the formation of very heavy tarry residues, 25 which very readily form carbon, and others upon being cracked tend to decompose direct into carbonaceous matter. By preventing the formation of more unsaturated bodies or aromatics than contained in the original stock, I am able to crack the resultant distillate with a minimum production of heavy tarry residue and carbonaceous matter. In natural crude petroleum oils there are varying percentages of unsaturated hydrocarbons which in some cases may be as high as 50%. I do not confine myself to any fixed percentage of hydrogen. By my method, whether carried out continuously or under

batch operations, by distillation under a reduced pressure, less than atmospheric pressure, there is substantially no further production of unsaturated hydrocarbons of such class that tends to form such undesirable tarry bodies or carbonaceous matter when the resultant distillate is subjected to a cracking process.

An object of the invention is to produce first, a relatively uniform high boiling point hydrocarbon distillate or fraction, either from a crude oil, a residuum or from a previous distillate, which shall contain the highest possible hydrogen content, in order that the same may be cracked to produce low boiling point hydrocarbons, or motor spirits, therefrom most advantageously, and, second, to provide as a part of such process for the cracking thereof to produce the desired low boiling point hydrocarbons or motor spirits.

By my invention I provide a combined process whereby there is first produced under a pressure less than atmospheric a relatively uniform high boiling point hydrocarbon distillate, substantially uncracked and containing the highest possible hydrogen content derivable from the stock employed and which distillate may be introduced into the second step of the process and cracked to produce low boiling point hydrocarbons with the minimum production of carbonaceous matter or tarry bodies, thereby substantially eliminating the usual disadvantages and troubles attendant from the production of carbonaceous matter and tarry bodies in a cracking apparatus or process. In the preferred form of my invention I first produce by distillation under a pressure less than atmospheric a relatively uniform high boiling point hydrocarbon distillate and then subject such distillate to destructive distillation.

Broadly, my invention consists in maintaining, first, a distilling operation at a substantially constant reduced pressure, so that the vaporizing temperature of the oil under distillation is below its decomposing or cracking temperature, and thus maintain a maximum hydrogen content in the vaporized distillate, and thereafter cracking this distillate to produce a low boiling point hydrocarbon oil.

In its detailed or more specific form the

first distilling operation is preferably carried on continuously, and the cracking operation is preferably performed as a continuous cracking operation, or step.

5 More specifically, the preferred embodiment of my invention consists in maintaining, first, a distilling operation at a substantially constant reduced pressure, so that the vaporizing temperature of the oil 10 under distillation is below its decomposing or cracking temperature, and thus maintaining the maximum hydrogen content in the vaporized distillate, preferably continuously introducing the oil to be distilled, 15 preferably continuously withdrawing the vapors of such distillation, and preferably continuously withdrawing the residual oils, and second, in performing the cracking operation by continuously introducing the 20 high boiling point distillate so produced by the vapors of the first distillation, into a cracking system or apparatus, maintaining in such cracking apparatus or system during the cracking operation a substantially 25 constant volume of such distillate under a pressure greater than atmospheric and at a substantially constant pressure and temperature sufficient to crack such distillate, continuously withdrawing the low boiling point fraction produced as vapor and substantially continuously withdrawing 30 the residual oil.

According to present day practice the cracking of petroleum oils is accompanied 35 by the deposition of carbonaceous matter within the heating element of the system. Also the distillation of crude petroleum under atmospheric pressure is accompanied by carbonaceous depositions on the still bottoms. Such depositions retard the conduction of heat through the metal. This results not only in the loss of heat but also in a slow destruction of the apparatus due to the over-heated condition of the metal. 40 Also with such depositions the apparatus cannot be operated continuously but must be shut down at intervals to clean out the accumulations. This results in loss of time, 45 efficiency and capacity.

50 The invention will be more readily understood by reference to the accompanying drawings in which an apparatus is indicated by means of which the preferred embodiment of my process may be carried out. 55 In these drawings:

Fig. 1 is a plan view of so much of the apparatus as is utilized in the first distillation under reduced pressure, and

Fig. 2 is a side elevation thereof.

60 Fig. 3 is a diagrammatic illustration of the apparatus, wherein the second distillation or cracking is performed.

Figs. 1 and 2 illustrate an apparatus for the continuous distillation of a high boiling point fraction and by means thereof the

first part of my process may be readily understood. I do not, however, necessarily limit my invention to such a continuous step or process.

Referring to Fig. 1—1 indicates a storage tank for the oil to be distilled. This tank is connected by a pipe 2 to a pump 3. The pump 3 discharges into a pipe 4 which leads to the heat exchanger 5. The oil to be distilled passes through the pipe coil 6 in the heat exchanger 5 and then into and through the pipe coil 8 of the heat exchanger 7, thence similarly through the heat exchanger 9 in pipe 10 and then into the tar heat exchanger 11. From the latter 80 the oil passes into the pipe 12 and is discharged continuously into the still 14.

The passage of the oil as described from storage pipe 1 to a still 14 is continuous and is preheated by the outgoing oil vapors 85 from stills 14, 35 and 56 by means of the heat exchangers 5, 7 and 9 which are arranged in a series so that the greatest heat exchange possible is effected. From heat exchanger 9 the oil to be distilled passes 90 through heat exchanger 11 wherein said oil is further heated by an exchange of heat from the outgoing hot residual oil. While this is the preferred order and arrangement, this order of preheating the incoming oil to 95 be distilled may be varied or changed as desired.

From the still 14 the oil passes through pipe 33 into still 35 and in like manner the oil from still 35 passes through the pipe 100 54 into the still 56. These stills are heated in any usual or preferred manner. The temperature of the oil as maintained in stills 14, 35 and 56 is such as to vaporize the desired fractions therein. The temperature maintained in the still 14, 35 or 56 to obtain the desired fraction depends upon the rate of distillation and the reduction of pressure upon the system. A reduction in pressure lowers the vaporizing point of 110 the desired fraction. This distillation may be carried out either with or without the introduction of steam.

83 indicates a pipe in an equalizing line common to the stills 14, 35 and 56 whereby 115 the pressure maintained in said stills is the same at all times.

76 indicates a pipe to conduct the hot residual oil to the tar heat exchanger 11 connected to the suction side of the pump 77. 12 Pump 77 discharges into a line which leads into a tar cooler 78 connected by a pipe 79 to storage tank 80. The flow of oil through the system is regulated by means of the pump 77.

15, 36 and 57 represent vapor lines which 125 conduct the products of distillation to vapor heat exchangers 5, 7 and 9 where a fraction of the vaporized oil or oil and steam is condensed and conducted through condensers 94, 92, 93, and thence by pipes 25, 46 and 67 130

to look boxes 26, 47 and 69. Suitable look boxes 26, 47 and 69 are connected to receivers which may be termed vacuum pots 28, 49 and 71 by pipes 27, 48 and 70. These vacuum pots 28, 49 and 71 are connected to pumps 30, 51 and 73 which pump said oil or oil and water to storage tanks 32, 53 and 75 through pipes 91, 90 and 74.

The necessary reduction of pressure or 10 vacuum is maintained on the system by vacuum pump 82 which is connected to receivers 19, 28, 40, 49, 61 and 71 by means of a pipe 95 and manifold pipe 81.

Preferably duplicate storage tanks are 15 provided for each still. Therefore in the drawings I have indicated storage tanks 23, 44, and 65 to which the distillate from the respective stills 14, 35, 56 may be conducted and have shown duplicate pumps 21, 42, 43, 20 by which the distillate from said respective stills is pumped to such storage tanks. 17, 38, 59, indicate the look boxes and 19, 40, 61 the receivers or vacuum pots in the line or system to such storage tanks 23, 44, 65, respectively.

In this apparatus as thus indicated for performing the first distillation I have indicated a battery of three stills, but my invention is not limited to the use of any particular number of such stills, since a greater or less number may be used in accordance with the production desired.

It is obvious that suitable valves may be provided in connection with the pipe 83 so that each of the stills may be operated without equalization with reference to the other or any coupling of the stills together for such equalizing purposes may be provided.

In Fig. 3 tanks 101 and 112 represent suitable storage vessels for the distillate or oil to be cracked. These are provided with suitable connections which lead to the receiving tanks 23, 44, 65, 75, 53 and 32 connected by manifold pipe 100. (See Fig. 1).

In Fig. 3 is illustrated the preferred form of apparatus for the second distillation or cracking operation. In such Fig. 3, 102 and 113 represent pumps for handling the distillate to be cracked and discharged into pipe 103 through a valve 114 into an evaporator 105. 106 represents a circulating pump connected on its suction side with a pipe 107 to the evaporator 105 and on its discharge side with a pipe 108 leading to the heating element, preferably a coil 109 in a furnace 110, being connected by a suitable pipe 111 to the evaporator 105.

116 is the vapor line from the evaporator 105; 117 represents a dephlemator in said line 116. 118 indicates a condenser connected with said dephlemator; 119 represents a suitable receiver connected with the condenser and 120 a valve whereby the pressure may be released or regulated and the condensate delivered for storage.

121 represents a discharge pipe from the evaporator 105; 122 a cooler to which the pipe 121 leads. 123 a discharge valve from the cooler and 124 a reservoir.

125 represents a receiving pan in the evaporator 5 connected to a pipe 126. 127 is a T with an open end opening into the connection of the pipe 107 through the end of the evaporator 105.

The apparatus thus illustrated in Fig. 3 is a preferred form of apparatus which I prefer to use in the cracking step of my process. My improvement in this step of the process, which improvement I preferably utilize when it is desired to secure all of the ultimate advantages of my invention in its most specific and complete form, consists in intermingling with the relatively high boiling point distillate produced by the first step of the process, a relatively non-crackable fraction or distillate which may be any hydrocarbon oil which is suitable to the heat and pressure employed in the cracking step of my process, such latter oil I term herein "solvent oil." Such suitable oil may, for example, be a distillate from the so-called refractory California crude oil which is an oil of relatively low boiling points containing an unusually high percentage of naphthalene and aromatic hydrocarbons or it may be any low boiling point fraction of the same, or any other oil which will be substantially unaffected at the pressure and temperature employed in the cracking step of the process.

The function of the solvent oil as thus used in the cracking step of my process is to keep the heavy bodies resultant from the cracking in dilute condition or in solution so that the resultant heavy bodies may be discharged from the system in solution or in dilute condition, thus substantially preventing the deposition of carbon in the apparatus or system.

From the evaporator 105 the solid hydrocarbons, heavy bodies or tarry residues in solution or in dilute condition in the solvent oil are discharged in the valve 121 and cooler 122 into the receiver 124 at such a rate as to keep the saturation of the solvent oil with the heavy bodies, heavy hydrocarbons or tarry residues therein below such a degree of concentration that upon further circulation and heating such solvent oil may take into solution the further high boiling point fractions produced from the crackable oil without permitting such heavy hydrocarbons to become too concentrated in the apparatus.

If the solvent oil is permitted to become overcharged with such heavy hydrocarbons deposition takes place as these heavy hydrocarbons take the brunt of the heat and unless held in solution or in dilute condition by the solvent oil becomes further reduced to carbon. The degree of concentration, (of the solvent oil and high boiling

point fraction produced by the cracking of the crackable oil,) which may be permitted in the operation of my process without danger of deposition will, of course, depend 5 upon the oils charged into the system, as for example, the carbon residue test should not exceed ten times that in the charged oils. This is merely an example and will vary with the oils. In the cracking of 10 certain petroleum distillates there may be produced from the cracking operation itself, sufficient solvent or non-crackable oil of unsaturated form to keep the solid hydrocarbons, heavy bodies or tarry residues in solution or in dilute condition so that no deposition will form on the metal surfaces of the heating element, in which case it is unnecessary to add a separate solvent or non-crackable oil from an outside source. I therefore 15 do not limit myself to the use of a solvent or non-crackable oil to be introduced from an outside source, since sufficient may be produced in the operation when certain petroleum oils are used.

20 A certain amount of non-crackable or solvent oil passes off with the solid hydrocarbons, heavy bodies or tarry residues in solution or in dilute condition. This may be replaced from storage as required.

25 As an example of the proportion of the oil to be cracked as to the proportion of solvent oil, I add one volume of the former to as much as three or five volumes of the latter in the system at any given time. This 30 may be varied in accordance with the oils treated. As an example of a desirable cracking pressure and temperature for the oil to be cracked, I give 105 to 120 pounds absolute and 745° F.-800° F., but it is understood that these proportions and the 35 pressure and temperature may vary according to the oils used.

40 In practice the solvent oil and the oil to be cracked may be mixed and thus introduced not only in charging the apparatus for starting the cracking distillation but also in the continued operation thereof.

45 It is also obvious that any relatively low boiling point oil may be used as the solvent oil provided it is substantially unaffected at the pressure and temperature of the operation.

50 By constantly feeding into the apparatus or system such a quantity of the solvent oil and oil to be cracked as will maintain a substantially constant volume in the apparatus and maintain continuous cracking at substantially the determined pressure and temperature, a substantially uniform fraction 55 is continuously produced during the cracking operation.

55 While I have thus referred and do hereafter refer in the claims to the solvent oil and the oil to be cracked as two oils it will 60 be understood that I do not limit my inven-

tion to the use of two distinct oils but include as within my process and invention and within the cracking step thereof the cracking of any oil which contains fractions, one of which will be cracked at a given 70 pressure and temperature and another fraction which will be substantially unaffected by pressure and temperature and which will act as a solvent oil as heretofore explained. It is thus obvious that I am not necessarily 75 limited in my process to the use of a solvent oil produced by the first step of my process.

It is also to be understood that my method is not confined to the use of any particular solvent oil, the distillate from refractory 80 California crude mentioned being given merely as an example of a solvent oil which is relatively unaffected by the pressure and temperature to crack the oil to be treated.

85 In the appended claims I refer to a relatively high boiling point fraction or distillate produced from a petroleum oil by distillation at a reduced pressure less than atmospheric, whereby in such distillate the maximum hydrogen content of such petroleum oil is conserved, as a distillate composed of substantially saturated hydrocarbons to distinguish the same from a distillate in which either unsaturated hydrocarbons or aromatics formed by distillation are 90 present, which tend either to such polymerization or to decomposition into carbonaceous matter, as before explained.

I claim:—

1. The art of cracking petroleum oil to 100 produce a low boiling point distillate from a relatively higher boiling point fraction, which includes distilling an oil under a reduced pressure less than atmospheric whereby decomposition is substantially prevented, 105 and then subjecting a relatively high boiling point fraction thus produced to a temperature and pressure sufficient to crack the same to produce a low boiling point distillate.

2. In the art of producing a low boiling 110 point distillate from a relatively higher boiling point fraction of a hydrocarbon oil, distilling the oil under a reduced pressure sufficient to lower the vaporizing temperature of 115 such oil, thereby producing a relatively high boiling point fraction thereof with the hydrogen content of the original oil substantially maintained in said fraction, and thereafter subjecting such fraction to a temperature 120 and pressure sufficient to crack the same to produce a low boiling point distillate.

3. In the art of producing a low boiling point distillate from a higher boiling point 125 distillate of a petroleum oil, distilling the oil under a reduced pressure sufficient to lower the vaporizing temperature of the oil below its decomposing temperature thereby producing a relatively high boiling point 130

fraction and whereby the formation of unsaturated hydrocarbons in said fraction is prevented, and thereafter subjecting such fraction to a temperature and pressure sufficient to crack said fraction to produce a relatively low boiling point fraction.

4. The improvement in cracking a relatively high boiling point hydrocarbon oil to produce a relatively low boiling point distillate which consists in continuously circulating through a closed system, a relatively high boiling point distillate, composed of hydrocarbons having a hydrogen content corresponding substantially to the hydrogen content of the corresponding fraction of the original oil, in conjunction with a solvent oil; maintaining in said system a pressure and temperature required to crack said distillate; continuously passing out of the system the low boiling point vapors from said cracked oil, and continuously removing from said system the resultant solvent oil solution.

5. In the method of cracking a relatively high boiling point hydrocarbon to produce a relatively low boiling point distillate, the step which consists in continuously circulating conjointly a relatively high boiling point distillate, composed of hydrocarbons having a hydrogen content corresponding substantially to the hydrogen content of the corresponding fraction of the original oil in conjunction with a solvent oil under conditions of pressure and temperature adapted to crack only said distillate, whereby the relatively higher boiling point fractions of such distillate are carried in dilute condition by said solvent oil.

6. The process of cracking a relatively high boiling point hydrocarbon to produce a substantially uniform relatively low boiling point distillate, which consists in continuously feeding into and rapidly moving through a closed system a relatively high boiling point distillate, composed of hydrocarbons, having a hydrogen content corresponding substantially to the hydrogen content of the corresponding fraction of the original oil, and a solvent oil, maintaining in said system a substantially constant volume, pressure and temperature, said temperature and pressure being that adapted to crack said high boiling point distillate, whereby the relatively higher boiling point fractions from said distillate are carried in dilute condition by said solvent oil, continuously passing off from the system the vapors of distillation, and maintaining the resultant solution by dilution and suitable discharge

from becoming sufficiently concentrated to cause deposition in the system. 60

7. The herein described method of cracking a relatively high boiling point hydrocarbon to produce a substantially uniform relatively low boiling point distillate, which consists in continuously feeding into and rapidly circulating through a closed system a relatively high boiling point distillate composed of hydrocarbons, having a hydrogen content corresponding substantially to the hydrogen content of the corresponding fraction of the original oil, and a solvent oil, maintaining in the system a cracking pressure and temperature required for the first named distillate but ineffective to crack the solvent oil, the heat being applied to one portion of the system, whereby through said pressure and temperature the first named distillate only is cracked and the relatively higher boiling point hydrocarbons produced by such cracking are carried in dilute condition by the solvent oil, continuously passing off from the system at points removed from said portion to which the heat is applied the low boiling point vapors of distillation, and the resultant residual solution. 75 80

8. The process of producing low boiling point distillate from hydrocarbon oil which consists in distilling an oil under a reduced pressure sufficient to lower the vaporizing temperature below the decomposition temperature of such oil, continuously circulating conjointly a relatively high boiling point distillate thereby produced conjointly with a solvent oil under conditions of pressure and temperature adapted to crack only said 90 distillate, whereby the relatively higher boiling point fractions from such distillate are carried in dilute condition by said solvent oil, withdrawing the resultant low boiling point vapor, and discharging the resultant 95 solvent oil solution. 100

9. In the art of producing a low boiling point oil from a relatively higher boiling point fraction of a petroleum oil, that step which consists in producing such relatively 105 higher boiling point fraction by distillation under a reduced pressure less than atmospheric and in the absence of substantial cracking thereby preserving the maximum hydrogen contents of such fraction. 110
